UNITED STATES PATENT OFFICE.

CHARLES W. DAKE, OF CHICAGO, ILLINOIS, ASSIGNEE TO THE FILE NATIONAL COMPANY, OF CHICAGO, ILLINOIS, A CORPORATION OF NEW JERSEY.

HEADLIGHT.

Application filed July 21, 1918. Serial No. 312,261.

To all whom it may concern:

Be it known that I, CHARLES W. DAKE, a citizen of the United States, residing at Chicago, in the county of Cook and State of Illinois, have invented a certain new and useful Improvement in Headlights, of which the following is a specification.

My invention relates to headlights and particularly to those adapted for use with locomotive engines. Through long usage the practice of making locomotive headlights of approximately eighteen inches in diameter has become fixed in the art. Were a locomotive headlight to be made of say 10 nine inches in diameter although it might give sufficient light for all necessary purposes, it would not serve, as it might not be recognized as a locomotive headlight. So firmly fixed has this idea become that it has 20 been found impossible to depart materially from the diameter of eighteen inches in making locomotive headlights.

With the development of higher powered lights it has been found unnecessary and 25 difficult to have a higher power beam of so great diameter, and it has become desirable 30 from every point of view to have the beam smaller and yet for the reasons above outlined it is not possible to reduce the total size of the lighted area of the headlight. It is therefore one of the objects of my invention to produce a headlight which will have a sufficient enlarged illuminated area and which in addition will have a smaller and 35 more intense beam of light in combination therewith. I attain this result by a combination of a small exceedingly efficient or bright reflector working with a small lens and a large less efficient or duller reflector 40 and plain glass covering the entire front of the illuminated area. My invention is illustrated more or less diagrammatically in the accompanying illustrations, wherein—

Figure 1 is a front elevation; and 45 Figure 2 is a vertical section on the line 2—2 of Figure 1.

Like parts are indicated by like characters throughout

A is a headlight casing, enclosing and supporting the bulk of the other headlight parts. It has the enlarged forward rim A¹ adapted to receive a front glass assembly. Its inner surface is lined with porcelain as at A² and thus comprises a reflector. A³ is 55 an inner supporting frame integral with the

member A and adapted to support the main reflector B. This reflector is spherical in shape toward its center as at B¹ and becomes parabolic towards its edges near B². B³ is a cup shaped member adapted to support the reflector B and hold it in position. It has the rearward projection B⁴ which penetrates within the cup B⁵ of the rear casing cover B⁶. B⁷ is a spring in the cup B⁵ adapted to cushion the reflector. B⁸ is a felt packing adapted further to cushion the reflector.

C is the light source in this case an incandescent light. D is the glass holding rim which encloses the plain glass D¹. D² D³ are arms extending inwardly and rearwardly from it and supporting the annular member D⁴ in which is positioned the small lens E.

I have described in detail a particular construction embodying the invention, but it is of course evident that the parts may be varied without departing materially from the spirit of the invention as embodied in the claims hereto appended, and I therefore do not wish to limit myself to the particular construction shown.

The reflector B is preferably glass and coated with reflecting material on the back, whereas the reflector A² may be a reflecting surface developed on or applied to the interior of the casing, or a separate reflector inserted.

The use and operation of my invention are as follows:

The bulk of the light rays from the light source are gathered by the small powerful reflector and reflected directly forward through the lens and are by it concentrated and projected in a narrow high power beam of light. That part of the light which does not fall upon the small reflector or which falling upon it is not reflected through the lens, is reflected from the larger porcelain reflector in the main casing and so passes out through the plain glass front cover. Thus the headlight gives a clearly illuminated surface of a diameter of eighteen inches and also a powerful concentrated narrow beam of light, in this case some eight inches in diameter at its source.

I call the central reflector the primary reflector and the exterior or annular reflector the secondary reflector, for the first is intended to give the strong beam of light which will illuminate the track far in advance of

the locomotive, while the second is intended to add to the nearby illumination and also to give the light the appearance of being of the usual locomotive headlight size. I have not 5 shown many of the parts which would necessarily be applied to the structure because they form no part of this invention, for example: in the casing there is left sufficient room at the bottom for the insertion of a 10 proper support and adjusting device for the electric lamp so that it can be focused. The arrangement is, of course, particularly applicable for use with electric lamps though I would not wish to be confined to that use.

15 The light from the lamp passes directly to the lens and also to the secondary reflector and primary reflector. The light is largely caught in the primary reflector and reflected from it toward the lens. With some forms 20 of primary reflector, as for example, in case, it is made non-parabolic or shallower than the preferred form illustrated, some of the light may be reflected therefrom toward a secondary reflector, and hence it will be 25 passed forward to the plain glass. Some of the light falls directly upon the secondary reflector and is thence reflected through the plain glass.

I claim—

30 1. In a headlight, the combination of a

primary reflector with a secondary reflector surrounding it, the primary reflector adapted to project a beam of light of high intensity, the secondary reflector adapted to project a surrounding beam of relatively low 35 intensity.

2. In a headlight, the combination of a primary reflector with a secondary reflector, and a lens in front of the primary reflector only, said lens adapted to project light from 40 said primary reflector in a beam of small diameter and high intensity, said secondary reflector adapted to project a surrounding beam of relatively large diameter and low intensity. 45

3. In a headlight, the combination of a primary reflector with a secondary reflector, and a lens in front of the primary reflector only, said primary reflector adapted to project its light only through said lens, the 50 secondary reflector adapted to project no light through said lens.

In testimony whereof, I affix my signature in the presence of two witnesses this 17th day of July, 1919.

CHARLES W. DAKF
